UNITED STATES PATENT OFFICE.

ERNEST H. SHAFF, OF GRAND HAVEN, MICHIGAN, ASSIGNOR TO WILLIAM H. KELLER, INC., OF GRAND HAVEN, MICHIGAN, A CORPORATION OF MICHIGAN.

PRESSURE-FLUID-ACTUATED TOOL.

Application filed December 6, 1920. Serial No. 428,429.

The invention has general reference to pressure-fluid-actuated tools and more particularly to tools of this class commonly known as jamb riveters. Such riveters are especially constructed for use in limited or restricted spaces and while the cylinders are made of relatively short length their internal diameters are relatively large so that the volumetric capacity of the cylinder is substantial. When, therefore, the supply of motive fluid is not maintained at high pressure, as is frequently the case because of a long and restricted air-line, the rapid and relatively free expansion thereof when admitted to the rear end of the cylinder to drive the piston forwardly results in a sudden drop in pressure in the cylinder.

It is common practice in tools of this character to utilize a portion of the motive fluid admitted to the rear end of the cylinder, for shifting the valve member as the piston approaches the forward limit of its movement, the flow of the motive fluid being controlled by the piston in its movement. I have found that in the case of large capacity cylinders, as, for instance, those of jamb riveters, above referred to, the return movement of the valve member by the pressure fluid admitted to the cylinder to drive the piston forwardly, is not sufficiently rapid or positive for the efficient operation of the tool.

The primary object of my invention, therefore, is to provide improved means for effecting the positive rearward movement of the valve member and thus improve the efficiency of the tool.

More specifically stated, the invention has for its aim the provision of means controlled by the initial rearward movement of the valve member for admitting pressure fluid directly from the source of supply to the valve member whereby to insure that it shall be shifted speedily and positively to its rearward position.

A further object is to deflect such live motive fluid from the valve member, after effecting the rearward movement thereof to the forward end of the cylinder to return the piston, thus relieving the valve member from the force of such pressure fluid and permitting its reverse or forward movement.

Other and incidental objects of the invention include the provision of a practical

tool of simplified construction and arrangement.

55

In the accompanying drawings, in which I have illustrated a preferred embodiment of my invention, Figure 1 is a central vertical sectional view through a tool of the jamb riveter type. Fig. 2 is a similar view but showing the valve member shifted into a position to effect the return of the piston.

60

The tool comprises generally a cylinder 3 having a piston chamber 4 in which a piston 5 is reciprocable into and out of engagement with a rivet set 6. 7 designates generally the valve mechanism for controlling the piston. The cylinder is mounted within a housing 8 so as to be movable forwardly therein under the action of pressure fluid admitted into the rear end of the housing which is closed by a cap 9. A passageway 10 for pressure fluid is provided by a stem portion 11 of the cap into which a suitable handle (not shown) is adapted to be entered, such handle being provided with the usual motive fluid controlling valve.

65

The cylinder 3 is arranged to fit neatly at its rear end within the housing 8, and at its forward end is reduced in diameter to provide between it and the housing an exhaust chamber 12. At its forward end the housing is shaped to provide an inturned annular boss 13 for slidably engaging the periphery of the forward end of the cylinder and closing the forward end of the chamber 12. A port 14 leads from the forward end of said chamber 12 to the atmosphere.

70

The cylinder 3 is made of relatively short length, but of comparatively large internal diameter to provide the piston chamber 4. The piston 5 is also made of relatively short length, and in the operation of the tool engages the rivet set 6 or other tool mounted in the forward end of the cylinder. Any suitable means may be employed to retain the rivet set in position such, for example, as that illustrated generally at 15.

75

The valve mechanism comprises a casing 16 composed of two annular interfitting sections 16^a and 16^b entered within the rear end of the cylinder in axial alinement with the piston chamber and held in position by means of an end plug 17 screw-threaded into the rear end of the cylinder. The sections 16 of the casing 16 are preferably rabbeted so

80

85

90

95

100

105

as to interfit, and to receive the casing the rear end of the cylinder is formed with an enlarged bore providing a shoulder 16^c against which the forward section 16^b of the 5 casing is held by the plug 17. The casing 16 is so arranged within the cylinder that a portion of the rear end of the cylinder protrudes rearwardly beyond the casing sufficiently to receive said plug. Suitable means 10 may be employed for locking the plug in position within the rear end of the cylinder. Such means may, for example, comprise a spring clip 18 having a stem portion 19 adapted to enter registering radial grooves 15 20 and 21 in the rear end of the cylinder and in the rear face of the plug, respectively. This locking means is covered in my co-pending application Serial No. 427,687, filed December 2, 1920, and therefore is not illustrated and described in detail nor claimed herein. The registering grooves 20 and 21 also provide a passage establishing communication between the passageway 10 and a chamber 22 formed between the cap 9 and 25 the rear face of the plug 17. Pressure fluid is thus admitted constantly to the chamber 22 and acts upon the cylinder to force it forwardly in the housing 8 as limited by the space within which the tool is being used.

30 For the purpose of sealing the joint between the rear end of the cylinder and the housing, I preferably provide an annular packing member such as a leather ring 23 entered in an annular groove 24 which is 35 formed in the periphery of the cylinder and communicates by way of a duct 25 with the rear chamber 22. It will be seen that pressure fluid acting upon the ring 23 will expand it into engagement with the inner periphery of the housing and thus provide an 40 effective seal between these relatively movable parts.

The valve casing 16 is shaped upon its inner periphery to provide a valve chamber 45 coaxially of the piston chamber, in which a valve member 26 is reciprocable to control the admission and exhaust of pressure fluid to and from the cylinder and thereby to effect the reciprocation of the piston. In 50 the rear end of the casing 16 there is provided an annular groove 27 communicating by way of a duct 28 with an annular groove 29 in the forward face of the plug 17. The latter is in constant communication by way 55 of a port or ports 30 with the rear pressure chamber 22, so that pressure fluid is constantly present in the annular groove 29 and in the duct 28. The groove 27 in the inner periphery of the casing is adapted to be controlled by the rear end of the valve member 26.

An annular rear pressure chamber 31 is 60 provided at the rear of the valve chamber between the valve member and its casing. 65 This chamber 31 is in constant communica-

tion by way of a port 32 with the duct 28. The forward wall of said pressure chamber is formed by a flange 33 on the periphery of the valve member, and such wall constitutes the smaller pressure area of the valve member against which the pressure fluid in the chamber 31 constantly acts to shift the valve member 26 forwardly in the casing. 70

When the valve member 26 is thus shifted forwardly into the position which it occupies 75 in Fig. 1, pressure fluid is admitted to the rear end of the cylinder from the chamber 22 by way of the port 30, duct 28 and groove 27, and the piston is driven forwardly under the expansion of the high pressure fluid. As 80 the piston approaches the forward end of the cylinder the air or other pressure therein is permitted to exhaust from the forward end of the piston chamber by way of a longitudinal passageway 34 opening into the forward end of said chamber and extending rearwardly through the wall of the cylinder and into the valve casing section 16^b from whence it opens into an annular chamber 35 provided by a groove in the inner periphery 85 of said casing section. The latter groove is connected, in the forward position of the valve member, with a similarly formed chamber 36 by an annular groove 37 formed in the outer periphery of the valve member 90 at the forward end thereof. The chamber 36 communicates by way of an exhaust passage 38 with the exhaust chamber 12. Thus, in the forward movement of the piston, air or other pressure in the forward end of the piston chamber is permitted to escape to the atmosphere by way of the passage 34, chamber 35, groove 37, chamber 36, exhaust passage 38 and exhaust chamber 12. 95

A passage way 39 extends from substantially the center of the piston chamber rearwardly into the valve casing, and its rear end opens into the valve chamber through a transverse groove 39^a. Said groove is closed by the valve member in the rearward position thereof, and is connected, in the forward position of the valve member, by a groove 39^b with an annular pressure chamber 40 formed by means of an annular groove in the inner periphery of the casing 16. The valve member is provided with a peripheral flange 41 operable in said annular chamber 40, the forward side of said flange providing the larger pressure area of the valve member. As the piston in its forward movement uncovers the forward end of the passage 39, a portion of the pressure fluid admitted to the rear end of the cylinder to drive the piston forwardly, passes by way of the transverse groove 39^a and the groove 39^b into the annular chamber 40, and acts upon the larger pressure area of the valve member to force the latter rearwardly against the action of the pressure fluid acting upon the smaller pressure area in the an- 100 105 110 115 120 125 130

nular chamber 31. After the initial rearward movement of the valve member, the pressure fluid admitted to the passageway 39 is assisted by pressure on the extreme forward end of the valve member until the annular groove 36 is uncovered, whereupon the pressure fluid in the rear piston chamber exhausts through the annular groove 36 and the exhaust passage 38.

10 Leading from near the forward end of the piston chamber and also extending rearwardly to the annular chamber 40 is a passageway 42 whose opening into the piston chamber is so arranged as to be closed by the piston in the forward position of the latter. In its initial movement rearwardly the flange 41 of the valve member also uncovers a radial port 43 leading from the annular chamber 40 to a longitudinal passage 44 provided in the valve casing and communicating at its rear end with the annular groove 29. The port 43 is thus in constant communication with the supply of motive fluid, and as soon as the flange 41 partially uncovers the port in the rearward movement of the valve, live pressure fluid is admitted to the chamber 40 and to the larger pressure area of the valve member. At this time the forward end of the passageway 42 is closed so as to prevent the escape of the live pressure fluid from the chamber 40. This pressure fluid, therefore, acts to positively shift the valve member rearwardly to the position shown in Fig. 2 and to hold it firmly in such position.

In such rearward movement of the valve member, the transverse groove 39^a in the valve casing is closed by the valve member so as to prevent the flow of pressure fluid from the chamber 40 into the cylinder through the passageway 39; and communication between the annular chambers 35 and 36 at the forward end of the valve casing by way of the annular peripheral groove 37 in the valve member is cut off. At the same time communication is established between the annular chamber 35 and a radial passage 45 leading to the forward end of the passage 44 which communicates constantly with the source of pressure fluid supply. The chamber 35 communicates at all times by way of a port 35^a with the longitudinal passageway 34 leading into the forward end of the cylinder. Hence, it will be observed, in this position of the valve member the live pressure fluid admitted to the passage 44 is deflected from the valve member by being discharged into the forward end of the piston chamber to return the piston. Moreover, as the piston in its rearward movement uncovers the forward end of the passageway 42, motive fluid in the annular chamber 40 passes to the forward end of the piston chamber to assist in returning the piston.

55 In order that the pressure in the rear end

of the piston chamber shall be permitted to escape to enable the free return of the piston, the annular chamber 36 in the forward end of the valve casing is placed in communication with the piston chamber in such rearward movement of the valve member, and since such chamber 36 communicates with the exhaust passage 38, any pressure fluid remaining in the rear end of the piston chamber is permitted to exhaust to the atmosphere. It will, of course, be observed that as the valve member moves rearwardly, the flow of pressure fluid to the rear end of the piston chamber by way of the groove 27 is cut off.

By reason of the flow of pressure fluid through the passages 44 and 45 and passageway 34, and through the passageway 42, to the forward end of the cylinder to return the piston, pressure in the annular chamber 40 is relieved sufficiently to enable the pressure fluid acting upon the smaller pressure area of the valve member to again shift the latter forwardly whereby to again admit pressure fluid into the rear end of the cylinder to drive the piston forwardly for another cycle of operation.

To facilitate the rearward movement of the valve member, I preferably provide a port 46 leading from the piston chamber just forwardly of the valve casing to the annular chamber 31. Since the valve member in its rearward movement uncovers the annular chamber 36 at the forward end of the valve casing, pressure fluid entering the annular chamber 31 from the port 32 is permitted to exhaust from said chamber to the passage 38 by way of the piston chamber. The port 46 being made of larger capacity than the port 32, the pressure in the chamber 31 is quickly relieved.

A summary of the operation of the tool is as follows: Assuming the parts to be in the position shown in Fig. 1, pressure fluid is admitted from the passage 10 through the radial grooves 20 and 21 into the chamber 22 between the cylinder and the cap 9. Pressure fluid is thus admitted by the port 32 to the smaller pressure area of the valve to hold it in its forward position. At the same time, the motive fluid enters the rear end of the piston chamber by way of the annular groove 27 and drives the piston forwardly therein, the air or pressure in the forward end of the piston chamber exhausting by way of passageway 34, annular chambers 35 and 36, which are connected by the groove 37, to the exhaust passage 38.

In the forward travel of the piston, pressure fluid is admitted to the chamber 40 and exerts pressure upon the valve member's larger pressure area tending to force it rearwardly. When the piston has uncovered the forward end of the passageway 39, pressure fluid is admitted from the interior of

the piston chamber to the annular chamber 40. The valve member is thus given an initial rearward movement, whereupon the extreme forward end of the valve member is exposed to the pressure fluid in the rear piston chamber. As this end of the valve member has a larger surface area than the rear end of the valve member the action of pressure fluid thereon assists in the rearward movement of the valve. The port 43, communicating constantly with the source of pressure fluid supply, is uncovered by the flange 41 of the valve member, whence live pressure fluid is admitted to the chamber 40 and the valve member positively shifted rearwardly. In such a rearward position of the valve member, the flow of motive fluid into the cylinder by way of the passageway 39 is prevented since the transverse groove 39^a is closed by the valve member.

Upon the completion of such rearward movement of the valve member, the flow of pressure fluid to the rear end of the piston chamber is cut off and pressure fluid admitted to the forward end of the piston chamber by way of the passages 44 and 45, annular chamber 35, port 35^a and passageway 34 to return the piston. As the piston travels rearwardly, pressure in the rear end 30 of the piston chamber escapes to the atmosphere by way of the annular chamber 36 which communicates with the exhaust passage 38, communication between the chamber 36 and the interior of the piston chamber 35 having been established by the rearward movement of the valve member. The rearward movement of the valve member was further facilitated by the release of pressure from the annular chamber 31 by way of the port 46 and thence through the piston chamber to the exhaust passage 38.

The pressure in the annular chamber 40 having been relieved by the flow of live pressure fluid to the forward end of the cylinder through the passages 44 and 45, and the rear end of the ports 46 having been closed by the flange 33 of the valve member, live pressure fluid admitted to the annular chamber 31 by way of the port 32 shifts the valve member forwardly so as to admit pressure fluid into the rear end of the cylinder and drive the piston forwardly therein.

It will be seen that I have provided a pressure-fluid-actuated tool of a highly practical character. The construction is exceedingly simple and the operation efficient. The admission of live pressure fluid to the valve member under the control thereof, serves to insure that it will move speedily and positively to its rearward position even though a high line pressure is not constantly maintained. Moreover, the deflection of the pressure fluid from the valve member to the forward end of the piston chamber to re-

turn the piston, facilitates the forward movement of the valve member under the action of live pressure fluid from the source of supply.

It is to be understood that while I have herein illustrated and described the invention as applied to a jamb riveter, I contemplate the application of the invention to other tools of this general class. I also desire to have it understood that the invention is not to be limited, in the interpretation of the appended claims, to the details of construction and arrangement set forth, except as may be necessitated by the state of the prior art.

I claim as my invention:

1. A pressure fluid actuated tool having a piston chamber, a piston reciprocable in said chamber, a hollow valve member axially aligned with the rear end of said chamber and adapted to receive the piston, a passage opening into the piston chamber substantially centrally thereof and arranged to be uncovered by the piston in its forward stroke, a large pressure chamber for the valve member, said valve member being adapted when in its forward position to connect said pressure chamber with the rear end of said passage and to cut off such communication when in its rearmost position, and means operable during the initial portion of the rearward movement of the valve member to admit live motive fluid to said pressure chamber whereby to complete the rearward movement of the valve member.

2. A pressure fluid actuated tool having a reciprocating piston and a reciprocating valve, means operable in the forward stroke of the piston to admit pressure fluid to impart an initial movement only to the valve member, said admission of pressure fluid being cut off by such initial movement of the valve member, and means operable upon the initial movement of the valve member to admit live motive fluid to the valve to complete its shifting movement.

3. A pressure fluid actuated tool having a reciprocating piston and a reciprocating valve, means operable in the forward stroke of the piston to admit pressure fluid to impart an initial movement only to the valve member, said admission of pressure fluid being cut off by such initial movement of the valve member, means operable upon the initial movement of the valve member to admit live motive fluid to the valve to complete its shifting movement, and a passage opening into the forward end of the piston chamber and associated with the last mentioned means whereby when the valve member moves into its rearmost position motive fluid is admitted to the forward piston chamber to return the piston.

4. A pressure fluid actuated tool having a reciprocating piston and a reciprocating

valve, means controlled by the piston in its forward stroke for admitting pressure fluid to impart an initial rearward shifting movement to the valve, the valve in its said movement cutting off said admission of pressure fluid and rendering the said means inoperative, and means operable when said first mentioned means is rendered inoperative to admit live motive fluid to the valve to complete its shifting movement.

5. A pressure fluid actuated tool having a reciprocating piston and a reciprocating valve, means controlled by the piston in its forward stroke for admitting pressure fluid 15 to impart an initial rearward shifting movement to the valve, said means being also controlled by the valve in its said movement to cut off said admission of pressure fluid whereby to render the said means inoperative, means operable when said first mentioned means is rendered inoperative to admit live motive fluid to the valve to complete 20 its shifting movement, and means for relieving pressure in the rear piston chamber 25 during the latter portion of the movement of the valve.

6. A pressure fluid actuated tool having a reciprocating piston and a reciprocating valve, means including a passage controlled 30 by the piston in its forward stroke for admitting pressure fluid to impart an initial rearward shifting movement to the valve, said passage being closed by the valve in its said movement, thereby rendering said 35 means inoperative, means operative when said first mentioned means is rendered inoperative to admit live motive fluid to the valve to complete its shifting movement, means operable upon such initial shifting

movement of the valve to expose the forward 40 end of the valve member to the pressure fluid in the piston chamber, and means operable during the final portion of the movement of the valve to relieve the pressure in the rear piston chamber.

7. A pressure fluid actuated tool comprising, in combination, a cylinder having a piston reciprocable therein, a valve casing, a valve reciprocable in said valve casing, means to permit pressure fluid to reciprocate said piston, including an inlet passage to the forward end of said cylinder controlled by said valve, said inlet passage including a longitudinal passage in said valve casing constantly in communication with live motive fluid, means to reciprocate said valve including a peripheral flange on said valve, an annular chamber in said valve casing adjacent said flange, an inlet passage to said chamber controlled by said piston and adapted to admit pressure fluid from the cylinder to shift the valve rearwardly during the forward movement of the piston and a second inlet passage to said chamber to admit live pressure fluid to move the valve 60 rearwardly including a port connecting said chamber with a point in said passage in the valve casing, said port being opened by said valve in its rearward movement, the arrangement being such that upon completion of the 65 rearward movement of the valve the pressure fluid thereby admitted to the forward end of the cylinder passes across the end of said port.

In testimony whereof, I have hereunto set 70 my hand.

ERNEST H. SHAFF.
